UNITED STATES PATENT OFFICE.

WALTER E. HORROCKS, OF LAKEWOOD, OHIO.

MACHINE FOR MAKING BEADS.

1,415,566.

Specification of Letters Patent. Patented May 9, 1922.

Application filed June 1, 1920. Serial No. 385,859.

To all whom it may concern:

Be it known that I, WALTER E. HORROCKS, a citizen of the United States, residing at Lakewood, in the county of Cuyahoga and 5 State of Ohio, have invented certain new and useful Improvements in Machines for Making Beads, of which the following is a specification.

This invention is a machine for making 10 what are termed "beads" from strips of paper or the like. These beads are used for ornamental purposes on portières or the like, and are usually made of strips of wall paper which are cut in a certain way and then 15 rolled up, and a coat of varnish applied to finish the same.

This winding or rolling operation is ordinarily done by hand, the strips being rolled up on a small rod or pin from which the 20 completed bead is afterwards removed. The object of the invention is to provide an improved machine for doing this work, and the machine includes a mandrel to which one 25 end of the strip of paper may be attached, and this mandrel is then revolved and the paper is wound thereon, and the bead may then be stripped from the mandrel when 30 finished. The machine includes a table or guide formed of sheet metal, upon which the strip of paper may be laid as it is fed to the mandrel.

The invention is illustrated in the accompanying drawings in which Figure 1 is a front elevation of the machine. Fig. 2 is a 35 side elevation. Fig. 3 is a detail in section on the line 3-3 of Fig. 1. Fig. 4 is a plan showing a completed bead on the mandrel. Fig. 5 is a section on the line 5-5 of Fig. 4.

The machine comprises a base plate 6 bent 40 around at the front end to form a clamp 7 with a screw 8 by means of which the base may be fastened to the edge of a table or bench. On the plate 6 is mounted a spring tension plate or guide table 10 having the form of 45 an arch which extends between standards 9 at opposite sides of the base plate 6. This guide table 10 is made of sheet metal and serves to guide the paper strips to the mandrel as well as to regulate the pressure or 50 tension on the paper with respect to the mandrel. This adjustment is effected by varying the arch or convexity of the table by means of a rod 15 connecting opposite ends of the table, near the bottom thereof, 55 and provided with a thumb nut 16. By

taking up on the nut the table is bowed upwardly, to increase the pressure or tension, or by letting off the nut the arch or bow is flattened to decrease the tension, or accommodate thicker paper. 60

The mandrel 11 comprises a tube having a longitudinal slot 12 in its wall into which the end of the strip of paper may be inserted as indicated at 24 in Fig. 5, to start the bead. This mandrel is provided at one end 65 with a pinion 13 meshing with a gear 14 on a crank 22 supported by one of the standards 9, and by turning the crank the mandrel is rotated in an obvious manner. The mandrel is mounted in a socket bearing at 20 in the 70 top of one standard, and is extended outwardly as indicated at 25 to form a handle by which it may be lifted from the bearing through a slot 21 leading to the bearing. At the opposite end the mandrel is supported 75 in a socket bearing 17 pressed by a spring 18 in a tubular piece 19 mounted on the standard 9, the spring permitting the end of the mandrel to be pushed in to release the opposite end of the mandrel from the bearing 20 80 and permit it to be lifted from the machine. A ball bearing 18^a is interposed between the end of the spring 18 and the end of the mandrel which is supported by the socket bearing 17. The slot 12 is open at its left hand 85 end (in Fig. 1) to permit the bead to be stripped off of the mandrel.

In operation, the guide table 10 is adjusted by nut 16 to the desired tension or position, and the strip of paper is laid on the 90 table and its end engaged in the slot 12. The mandrel is then rotated by working the crank and the strip is wound on the mandrel to produce the bead shown in Fig. 4. The mandrel may then be pushed endwise 95 slightly against the ball and the tension of the spring 18 and lifted out of its bearings, and the bead is then stripped from the mandrel at its open end, and the mandrel may then be replaced in the machine for the next 100 operation. The device will be found very useful for the intended purpose and it is so simple that it may be operated by children.

I claim:

1. In a machine for winding paper beads 105 or the like, the combination of a frame having bearings, a mandrel removable from said bearings, and a guide table mounted on the frame and extending under the mandrel.
2. In a machine for winding paper beads 110

or the like, the combination of a frame having bearings, a mandrel removable from said bearings, and a guide table mounted on the frame and extending under the mandrel, said table being flexible and adjustable to vary its position with respect to the mandrel.

3. In a machine for winding paper beads or the like, the combination of a flexible arched table forming a guide, and a mandrel rotatable above said table, said mandrel being removable from the table to permit the bead to be stripped therefrom.

4. In a machine for winding paper beads

or the like, the combination of a frame having standards provided with bearings, a mandrel mounted in said bearings and removable therefrom, and an adjustable guide table extending between the standards and under the mandrel.

In testimony whereof, I do affix my signature in presence of two witnesses.

WALTER E. HORROCKS.

Witnesses:
